UNITED STATES PATENT OFFICE.

CHARLES M. STINE, OF WOODBURY, NEW JERSEY, ASSIGNOR TO E. I. DU PONT DE NEMOURS AND COMPANY, OF WILMINGTON, DELAWARE, A CORPORATION OF DELAWARE.

PROCESS OF PRODUCING EXPLOSIVE COMPOUNDS AND PRODUCT THEREOF.

1,309,551.

Specification of Letters Patent.

Patented July 8, 1919.

No Drawing.

Application filed July 20, 1916. Serial No. 110,278.

To all whom it may concern:

Be it known that I, CHARLES M. STINE, of Woodbury, in the county of Gloucester, and in the State of New Jersey, have invented a certain new and useful Improvement in Processes of Producing Explosive Compounds and Products Thereof, and do hereby declare that the following is a full, clear, and exact description thereof.

10 My invention relates particularly to a process for producing explosives of an advantageous character, and the product thereof. The object of my invention is to provide a process for producing explosives and particularly explosive compounds containing a nitro group and a nitrate group, or a plurality of such groups, and the product produced thereby. More particularly, the object of my invention is to provide a process 15 of producing explosive compounds containing a plurality of nitro groups and a plurality of nitrate groups. A further object of my invention is to provide compounds of this character in which a nitro group is located in the ring and a nitrate group is located in the side chain of the compound. I have found that of these compounds dinitrotolylene nitrate is a particularly advantageous product.

20 30 While my invention is capable of embodiment in many different forms, for the purpose of illustration I have described only certain forms thereof. For example, I may proceed as follows:—

35 The compound produced in accordance with my process may be, for example, any one of the following:

45 But, as I have pointed out above, I have found that dinitrotolylene-nitrate

50 is a particularly valuable product. In carrying out my process xylol may be chlorinated in direct sunlight at about a temperature of 100° C. the flow of chlorin being continued until a theoretical increase in

weight has been attained corresponding to the di-chlor derivative. When the mixture 55 has cooled down a mass of crystals separates out, which consist of phenyl-paradimethyl-chlorid. These crystals are filtered off and nitrated by applying a mixture of nitric and sulfuric acids according to the procedure 60 usually followed in nitration, preferably until the dinitro compound is obtained. The nitrated material is heated with pure water under a pressure of preferably 20 pounds per square inch, until the chlorine 65 atoms in the side chain have been replaced by hydroxyl groups. The aqueous solution is then evaporated to drive off the water and hydrochloric acid, and the dinitrophenyl-paradimethylol is obtained in well crystallized 70 form. The dinitrophenylparadimethylol is nitrated further by the application of a mixture of sulfuric and nitric acids in accordance with the procedure usually followed in nitration. A white crystalline 75 material is thus obtained, which can be filtered from the mixed acids, washed and neutralized and which, after drying, is suitable for use as an explosive, or as an ingredient in explosives. The explosive thus obtained 80 is exceedingly powerful and very stable.

Such compounds may also be prepared by other processes, as, for example, nitration of an aromatic hydrocarbon to the mono-, di- or 85 tri-nitro compound, chlorination of the di-nitro compounds to introduce chlorin into the side chain, hydrolysis of the chlor-nitro compound to produce a nitro hydroxyl compound and nitration of the nitro-hydroxyl 90 compound to produce a nitro nitrate.

While I have described my invention above in detail, I wish it to be understood that many changes may be made therein without departing from the spirit of my 95 invention. For example, I do not wish to limit myself to any particular method of preparation, and I wish it to be understood that the compounds produced in accordance with my invention may be used as such or in 100 mixtures of various kinds, as desired.

I claim—

1. A process of producing an explosive compound which comprises nitrating and halogenating an organic compound to introduce a nitro group and a halogen, hydrolyz-

ing to substitute a hydroxyl group for the halogen, and nitrating to substitute a nitrate group for the hydroxyl group.

2. A process of producing an explosive compound which comprises nitrating and halogenating a hydrocarbon to introduce a nitro group and a halogen, hydrolyzing to substitute a hydroxyl group for the halogen and nitrating to substitute a nitrate group for the hydroxyl group.

3. A process of producing an explosive compound which comprises nitrating and halogenating an aromatic hydrocarbon to introduce a nitro group and a halogen, hydrolyzing to substitute a hydroxyl group for the halogen, and nitrating to substitute a nitrate group for the hydroxyl group.

4. A process which comprises nitrating and halogenating xylol to introduce a nitro group and a halogen, hydrolyzing to substitute a hydroxyl group for the halogen, and nitrating to substitute a nitrate group for the hydroxyl group.

5. A process which comprises nitrating and halogenating an organic compound to introduce a nitro group and a halogen, hydrolyzing to substitute a hydroxyl group for the halogen, and nitrating to substitute a nitrate group for the hydroxyl group, the halogenation being continued until the di-halogen derivative is obtained.

6. A process which comprises nitrating and halogenating a hydrocarbon to introduce a nitro group and a halogen, hydrolyzing to substitute a hydroxyl group for the halogen, and nitrating to substitute a nitrate group for the hydroxyl group, the halogenation being continued until the di-halogen derivative is obtained.

40 7. A process which comprises nitrating and halogenating an aromatic hydrocarbon to introduce a nitro group and a halogen, hydrolyzing to substitute a hydroxyl group for the halogen, and nitrating to substitute 45 a nitrate group for the hydroxyl group, the halogenation being continued until the di-halogen derivative is obtained.

8. A process which comprises nitrating and halogenating xylol to introduce a nitro group and a halogen, hydrolyzing to substitute a hydroxyl group for the halogen, and nitrating to substitute a nitrate group for the hydroxyl group, the halogenation being continued until the di-halogen derivative is obtained.

9. A process which comprises nitrating and halogenating an organic compound to introduce a nitro group and a halogen, hydrolyzing to substitute a hydroxyl group for the halogen, and nitrating to substitute a nitrate group for the hydroxyl group, the initial nitration being continued until the dinitro compound is produced.

10. A process which comprises nitrating
65 and halogenating a hydrocarbon to intro-

due a nitro group and a halogen, hydrolyzing to substitute a hydroxyl group for the halogen, and nitrating to substitute a nitrate group for the hydroxyl group, the initial nitration being continued until the 70 dinitro compound is produced.

11. A process which comprises nitrating and halogenating an aromatic hydrocarbon to introduce a nitro group and a halogen, hydrolyzing to substitute a hydroxyl group for the halogen, and nitrating to substitute a nitrate group for the hydroxyl group, the initial nitration being continued until the dinitro compound is produced. 75

12. A process which comprises nitrating and halogenating xylol to introduce a nitro group and a halogen, hydrolyzing to substitute a hydroxyl group for the halogen, and nitrating to substitute a nitrate group for the hydroxyl group, the initial nitration being continued until the dinitro compound is produced. 80 85

13. A process of producing an explosive compound which comprises nitrating and halogenating an organic compound to introduce a nitro group and a halogen, hydrolyzing to substitute a hydroxyl group for the halogen, and nitrating to substitute a nitrate group for the hydroxyl group, and the halogenation being carried out before the initial nitration. 95

14. A process of producing an explosive compound which comprises nitrating and halogenating a hydrocarbon to introduce a nitro group, and a halogen, hydrolyzing to substitute a hydroxyl group for the halogen, and nitrating to substitute a nitrate group for the hydroxyl group and the halogenation being carried out before the initial nitration. 100
105

15. A process of producing an explosive compound which comprises nitrating and halogenating an aromatic hydrocarbon to introduce a nitro group and a halogen, hydrolyzing to substitute a hydroxyl group for the halogen, and nitrating to substitute a nitrate group for the hydroxyl group, and the halogenation being carried out before the initial nitration. 110

16. A process which comprises nitrating and halogenating xylol to introduce a nitro group and a halogen, hydrolyzing to substitute a hydroxyl group for the halogen, and nitrating to substitute a nitrate group for the hydroxyl group, and the halogenation being carried out before the initial nitration. 115

120

17. A process which comprises nitrating and halogenating an organic compound to introduce a nitro group and a halogen, hydrolyzing to substitute a hydroxyl group for the halogen, and nitrating to substitute a nitrate group for the hydroxyl group, the halogenation being continued until the dihalogen derivative is obtained, the halo- 125 130

genation being carried out before the initial nitration.

18. A process which comprises nitrating and halogenating a hydrocarbon to introduce a nitro group and a halogen, hydrolyzing to substitute a hydroxyl group for the halogen, and nitrating to substitute a nitrate group for the hydroxyl group, the halogenation being continued until the di-halogen derivative is obtained, the halogenation being carried out before the initial nitration.

19. A process which comprises nitrating and halogenating an aromatic hydrocarbon to introduce a nitro group and a halogen, hydrolyzing to substitute a hydroxyl group for the halogen, and nitrating to substitute a nitrate group for the hydroxyl group, the halogenation being continued until the di-halogen derivative is obtained, the halogenation being carried out before the initial nitration.

20. A process which comprises nitrating and halogenating xylol to introduce a nitro group and a halogen, hydrolyzing to substitute a hydroxyl group for the halogen, and nitrating to substitute a nitrate group for the hydroxyl group, the halogenation being continued until the di-halogen derivative is obtained, the halogenation being carried out before the initial nitration.

21. A process which comprises nitrating and halogenating an organic compound to introduce a nitro group and a halogen, hydrolyzing to substitute a hydroxyl group for the halogen, and nitrating to substitute a nitrate group for the hydroxyl group, the initial nitration being continued until the dinitro compound is produced, the halogenation being carried out before the initial nitration.

22. A process which comprises nitrating and halogenating a hydrocarbon to introduce a nitro group and a halogen, hydrolyzing to substitute a hydroxyl group for the halogen, and nitrating to substitute a nitrate group for a hydroxyl group, the initial nitration being continued until the dinitro compound is produced, the halogenation being carried out before the initial nitration.

23. A process which comprises nitrating and halogenating an aromatic hydrocarbon to introduce a nitro group and a halogen, hydrolyzing to substitute a hydroxyl group for the halogen, and nitrating to substitute a nitrate group for the hydroxyl group, the initial nitration being continued until the dinitro compound is produced, the halogenation being carried out before the initial nitration.

24. A process which comprises nitrating and halogenating xylol to introduce a nitro group and a halogen, hydrolyzing to substitute a hydroxyl group for the halogen, and

nitrating to substitute a nitrate group for the hydroxyl group, the initial nitration being continued until the dinitro compound is produced, the halogenation being carried out before the initial nitration.

70

25. A process which comprises nitrating and halogenating an organic compound to introduce a nitro group and a halogen, hydrolyzing to substitute a hydroxyl group for the halogen, and nitrating to substitute a nitrate group for the hydroxyl group, the halogenation being continued until the di-halogen derivative is obtained, both of the halogens being substituted by hydroxyl groups, the initial nitration being continued until the dinitro compound is produced.

75

26. A process which comprises nitrating and halogenating a hydrocarbon to introduce a nitro group and a halogen, hydrolyzing to substitute a hydroxyl group for the halogen, and nitrating to substitute a nitrate group for the hydroxyl group, the halogenation being continued until the di-halogen derivative is obtained, both of the halogens being substituted by hydroxyl groups, the initial nitration being continued until the dinitro compound is produced.

80

27. A process which comprises nitrating and halogenating an aromatic hydrocarbon to introduce a nitro group and a halogen, hydrolyzing to substitute a hydroxyl group for the halogen, and nitrating to substitute a nitrate group for the hydroxyl group, the halogenation being continued until the di-halogen derivative is obtained, both of the halogens being substituted by hydroxyl groups, the initial nitration being continued until the dinitro compound is produced.

85

28. A process which comprises nitrating and halogenating xylol to introduce a nitro group and a halogen, hydrolyzing to substitute a hydroxyl group for the halogen, and nitrating to substitute a nitrate group for the hydroxyl group, the halogenation being continued until the di-halogen derivative is obtained, both of the halogens being substituted by hydroxyl groups, the initial nitration being continued until the dinitro compound is produced.

90

29. An explosive containing an organic compound having therein a nitro group and a nitrate group, there being a plurality of one of said groups present.

95

30. An explosive containing an organic compound of the aromatic series, having therein a nitro group and a nitrate group, there being a plurality of one of said groups present.

100

31. An explosive containing an organic compound of the aromatic series having side chains and having a plurality of nitro groups in the ring and a plurality of nitrate groups in the side chains.

105

32. An explosive containing an organic compound of the aromatic series having side

110

130

- chains and having two nitro groups in the ring and two nitrate groups in the side chains.
33. An explosive containing an organic compound having a plurality of nitro groups and a plurality of nitrate groups.
34. An explosive containing an organic compound of the aromatic series having therein a plurality of nitro groups and a plurality of nitrate groups.
35. An explosive containing an organic compound of the aromatic series having side chains and having two nitro groups and two nitrate groups.
36. An explosive containing an organic compound of the aromatic series having therein two nitro groups and two nitrate groups.
37. An explosive composition containing an organic compound having therein a nitro group and a nitrate group, there being a plurality of one of said groups present.
38. An explosive composition containing
- an organic compound of the aromatic series, having therein a nitro group and a nitrate group, there being a plurality of one of said groups present.
39. An explosive composition containing an organic compound having a plurality of nitro groups in the ring and a plurality of nitrate groups in the side chains.
40. An explosive composition containing an organic compound of the aromatic series having side chains and having two nitro groups in the ring and two nitrate groups in the side chains.
41. An organic compound of the aromatic series having the formula:—

40

In testimony that I claim the foregoing I have hereunto set my hand.

CHARLES M. STINE.
